(57) **CLAIM**

The ornamental design for a tire, as shown and described.

DESCRIPTION

FIG. 1 is a perspective view of the tire of my design, according to a first embodiment;

FIG. 2 is a side elevation view of the tire of FIG. 1;

FIG. 3 is a side elevation view of the tire of FIG. 1, taken from the opposite side of that shown in FIG. 2;

FIG. 4 is a front elevation view of the tire of FIG. 1;

FIG. 5 is an enlarged, partial view of the tire of my design, taken from FIG. 1; and,

FIG. 6 is a perspective view of the tire of my design, according to a second embodiment.

The dash-dot-dot-dash lines define the boundaries of the claim. The broken line disclosure in the drawings depicts environmental subject matter forming no part of the claimed design. The tread pattern repeats over the circumferential surface of the tread. The lined surfaces of the embodiment of FIG. 6 designate color with no particular color being claimed thereby; the second embodiment of FIG. 6 in all other respects having the same appearance as the first embodiment.

1 Claim, 6 Drawing Sheets
